CARD CABINET

Glenn Theodore Gourley and Frank Joseph Malat, Youngstown, Ohio, assignors to The General Fireproofing Company, Youngstown, Ohio, a corporation of Ohio

Application September 14, 1934, Serial No. 744,062

9 Claims. (Cl. 45—94)

This invention relates to filing cabinets, and has particular reference to certain desirable improvements in filing cabinets especially designed for the filing of cards and the like and of the type comprising a casing having drawers slidably mounted therein and two or more trays slidably and removably mounted on each drawer.

One special object of the invention is to provide a novel drawer and tray latch combination comprising a latch individual to each drawer to hold the same in a closed position within the cabinet for ready withdrawal upon release of the latch, and a latch individual to each tray to positively hold the latter in a closed position relative to the related drawer when the latter is in a closed position, and to permit ready withdrawal or removal of the tray from the drawer when the drawer is moved to an open position.

Another special object of the invention is to provide a drawer latch having a plurality of finger engageable elements for actuation to release the same, and to locate said elements with respect to the handle of the related trays so that a person grasping the handle of any tray by one hand may, by a finger of the same hand, readily and easily effect release of the drawer latch to permit withdrawal of the latter and the trays carried thereby.

Another object of the invention is to provide novel drawer and tray latch devices and, in general, to provide a cabinet of the character stated having a latch combination as mentioned, which cabinet is of simple, sturdy construction and of relatively low production cost.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the drawings, wherein like characters of reference denote corresponding parts in the different views:—

Figure 1 is a perspective view of a cabinet constructed in accordance with the invention and showing one of the drawers withdrawn and the manner of removing a tray therefrom, and another tray being inserted into a drawer which is in a closed position.

Figure 2 is a detail perspective view of the rear end portion of one of the drawers and the rear end portion of a related tray showing the tray latch means.

Figure 3 is a detail horizontal sectional view showing the drawer latch; and

Figures 4, 5 and 6 are detail sectional views showing different positions of a tray relative to its related drawer.

Figure 7 is a detail sectional view on line 7—7 of Fig. 1 through the finger knob of the drawer latch.

Referring to the drawings in detail, A designates, generally, a filing cabinet casing which is formed preferably, but not necessarily, from sheet metal and which may be of any desired dimensions, said casing having slidably mounted therein in any known or desired manner, as by suspension means as illustrated conventionally in Fig. 1 and designated generally as 10, a plurality of open-top, open-front drawers 11 each comprising a bottom wall 12, side walls 13 and a rear wall 14.

The drawers 11 are arranged in superimposed relationship and may be of any desired height and detail construction. Preferably they correspond in width to the casing A, but the casing A may be of a width to accommodate two or more tiers of drawers arranged in side to side relationship and two or more tiers of drawers may be arranged therein. The drawers constitute holders for card trays designated generally as 15, and in this connection each drawer may be of a width to accommodate any desired plurality of card trays disposed in side to side relationship. Preferably, however, each drawer is of a width to accommodate two trays as shown.

On one of the side walls of the casing A at the side of each drawer compartment is suitably provided an abutment or keeper 16 for cooperation with a latch 17 carried by the related drawer at the front thereof to hold the drawer closed. In the present instance each keeper 16 comprises a tongue struck inwardly from the side wall of the casing and each latch 17 comprises a rod or bar disposed at the inner side of a reinforcing, finishing and stiffening flange 18 constituting a downwardly directed extension of the bottom wall of each drawer.

Each latch bar or rod 17 is of a length to completely underlie one tray compartment and at least a part of the other tray compartment of the related drawer, and each latch bar is provided with a pair of pins 19 projecting forwardly through related slots 20 in the related flange 18 whereby the latch bar is supported for longitudinal sliding movement transversely of the drawer.

The forward face of each keeper 16 and the related end of each latch bar 17 is inclined

5

40

45

50

55

rearwardly and inwardly so that when any given drawer is slid to a closed position within the casing A the latch bar rides over the keeper. Also, a suitable spring 21 connects each latch bar 5 with its related drawer and acts constantly to slide the latch bar in a direction to project the effective latching end of the same behind the related keeper 16 so that when any given drawer is closed it becomes automatically latched in that 10 position.

Each tray 15 is provided at its forward end with a handle 22 for use in withdrawing, removing and inserting the tray from and within its related drawer. Also, each latch bar pin 19 is 15 provided with a knob 23 exposed at the front of the flange 18 for finger manipulation to slide the latch bar to a disengaged position relative to its keeper 16 to permit withdrawal of the drawer. In this connection it will be observed 20 that the knobs 23 are related, one to each tray handle, and are so disposed relative to said handles, respectively, that when the trays are closed, a person grasping the handle of either tray with one hand may conveniently, by a 25 thumb or finger of the same hand, manipulate the related knob 23 to release the drawer latch 17.

Each drawer 11 is divided into two tray compartments by a central, forwardly and rearwardly extending partition 24 constituting a guide for the inner side of each of the two drawers 15 disposed in said compartments. On the other hand, guides 25 for the outer sides of the trays are fastened, respectively, against the inner faces of the drawer side walls 13.

Struck from or suitably secured to one of the guides 25 of each drawer near the inner end thereof is a laterally directed lug 26, a counterpart 26' of which projects from the remote side of the related partition 24, and each tray 15 is provided at its inner end with a corner recess 27 to accommodate the related lug when the tray is in a closed position. Within the recessed corner of each tray is a guide casing 28 and within each guide casing is slidably mounted for vertical movement a latch 29 for cooperation with the related lug 26 or 26'. Each latch 29 is urged constantly upwardly by a spring 30 and comprises a bar recessed at its rear to accommodate the related lug 26 or 26' and itself formed with a lug 31 having a beveled edge so that when the tray is slid to a closed position the latch 29 automatically engages its related lug and positively latches the tray against removal from its drawer as long as the latter is closed, since the latch 29 is inaccessible except when the related drawer is opened. However, the bottom of each drawer is cut away at its rear as at 32 so that any tray may be tilted upwardly at its front end to disengage its latch from the related lug when the drawer is opened, as illustrated in Fig. 6, thereby to permit the tray either to be slid outwardly or, if desired, to be entirely removed from the drawer.

From the foregoing it is clear that any drawer may be slid into or may be withdrawn from the casing A at any time; also, that any tray may be slid to a closed position within its related drawer at any time regardless of whether the drawer is open or closed. On the other hand, it is clear that if any particular drawer is closed, the related trays, if in closed position therein, cannot be withdrawn or removed therefrom until the drawer is opened. Accordingly, the tray handles constitute means to be grasped for the 75 purpose of withdrawing the drawers, and since

the drawer latch actuators 23 are related to and are disposed adjacent to the tray handles 22, respectively, where they may be manipulated to disengage the drawer latch by a finger or the thumb of the same hand which is engaged with either tray handle, it follows that any given drawer may be opened with great facility.

Preferably the pins 19 are provided with washers 33 to overlie and hide the slots 20 at all times. Preferably, too, the tray sides are, in effect, provided with recesses 34 extending downwardly from their upper edges near the fronts of the trays to afford finger access to cards or the like contained within the trays, but these are desirable features which may or may not be incorporated as desired.

Without further description it is thought that the features and advantages of the invention will be readily apparent to those skilled in the art, and it will of course be understood that changes 20 in the form, proportion and minor details of construction may be resorted to, without departing from the spirit of the invention and scope of the appended claims.

We claim:—

1. A filing cabinet comprising a casing, a drawer slidably mounted therein, releasable latch means to hold the drawer in a closed position within the casing, a tray slidably mounted within the drawer, releasable latch means to hold the tray in a closed position within the drawer, a handle for the tray, and an actuator for the drawer latch means located adjacent to said handle, said tray latch means being automatically operable upon closing of the tray when the drawer is closed to latch the tray closed and to positively prevent opening of the tray until the drawer is opened, and said drawer latch means being automatically operable upon closing of the drawer to latch the drawer closed until its latch 40 means is manually released.

2. A filing cabinet comprising a casing, a drawer slidably mounted therein, a plurality of trays slidably mounted within the drawer, latch means for holding the trays within the drawer, 45 each tray having a handle, latch means to hold the drawer closed, and a plurality of actuators for the drawer latch means individually related and located relative to the tray handles, respectively, so that a person grasping the handle of 50 any tray with one hand may, with a finger of the same hand, manipulate the related drawer latch actuator to effect release of the drawer latch.

3. A filing cabinet comprising a casing, a drawer slidably mounted therein, a plurality of trays 55 slidably mounted in side to side relationship within the drawer, a handle at the front of each tray, latch means for holding the trays within the drawer, and latch means to hold the drawer closed, said drawer latch means comprising a keeper on the casing and a cooperating latch element slidably mounted on the drawer and having a plurality of actuating devices individually related to and located adjacent to the tray handles, respectively, when the trays are closed.

4. A filing cabinet comprising a casing, a drawer slidably mounted therein, a plurality of trays 70 slidably mounted in side to side relationship within the drawer, a handle at the front of each tray, latch means for holding the trays within the drawer, and latch means for holding the drawer closed, said drawer latch means comprising a keeper on a side of the casing, a cooperating latch bar mounted on the front of the drawer 75

- for horizontal sliding movement between latched and unlatched positions, and a plurality of actuating elements for said bar individually related to the tray handles, respectively, and exposed at the front of the drawer adjacent to said handles. 5
5. A filing cabinet comprising a casing, a drawer slidably mounted therein, a tray slidably mounted within the drawer, releasable latch means to hold the drawer closed, a handle on the front of said tray, an actuating element for said drawer latch means exposed at the front of the drawer adjacent to said handle, and latch means to hold the tray within the drawer, said tray latch means being disposed to be inaccessible when the drawer and the tray are closed. 10
6. A filing cabinet comprising a casing, a drawer slidably mounted therein, a tray slidably mounted within the drawer, releasable latch means for holding the tray within the drawer, the tray having a handle, releasable latch means to hold the drawer closed, and an actuator for the drawer latch means located relative to the tray handle so that a person grasping the tray handle with one hand may, with a finger of the same hand, manipulate the drawer latch actuator to effect release of the drawer latch. 15
7. A filing cabinet as set forth in claim 6 in which the actuator for the drawer latch is disposed below the tray handle and is laterally shiftable to effect release of the drawer latch. 20
8. A filing cabinet comprising a casing, a drawer slidably mounted therein, a tray slidably mounted within the drawer, means for manual manipulation to slide the tray relative to the drawer, releasable latch means to hold the drawer closed, tray latch means effective when the tray is closed to prevent outward movement of the tray relative to the drawer as long as the drawer is closed, and an actuator for said drawer latch means disposed adjacent to said means for sliding the tray. 25
9. A filing cabinet comprising a casing, a drawer slidably mounted therein, a tray slidably mounted within the drawer, a handle at the front of the tray, latch means to hold the tray within the drawer, a keeper on the casing, a cooperating latch bar mounted on the front of the drawer for sliding movement between latched and unlatched positions, means tending constantly to move said bar to a latched position, and a bar actuator exposed at the front of the drawer adjacent to the tray handle when the tray is closed. 30
